CLAIM

The ornamental design for an elliptical plate, as shown and described.

DESCRIPTION

FIG. 1 is a top front perspective view of an elliptical plate showing my new design;

FIG. 2 is a top view thereof;

FIG. 3 is a bottom view thereof;

FIG. 4 is a side view thereof, the other side view being a mirror image thereof;

FIG. 5 is a front view thereof, the back view being a mirror image thereof;

FIG. 6 is a bottom front perspective view thereof; and,

FIG. 7 is a cross-sectional view of the elliptical plate taken along line 7-7 of FIG. 1.
